REEL OPERATING MECHANISM FOR DYEING MACHINES

George E. Drum and William H. Jaxheimer, Philadelphia, Pa., assignors to Smith, Drum & Company, Philadelphia, Pa., a corporation of Pennsylvania

Application April 12, 1932, Serial No. 604,690

10 Claims. (Cl. 8—19)

The present invention relates to dyeing apparatus and more particularly to an intermittently actuated material lifting device and control therefor.

5 In the operation of a new type of dyeing machine devised by these applicants (upon which applications for patents are now pending) where-in skeins of yarn are suspended from a perforated dye discharging support with means for lifting and changing the position of the skeins on such support, it has been found that different periods of operation for different grades and kinds of skeins are necessary for efficient operation. Also it has been found necessary to have 10 the rotary lifting device perform its operating cycle from the same initial starting position, which position has a definite spaced relation to the hanging yarn skeins.

Some of the objects therefore of the present 20 invention are to provide an improved dyeing or material treating machine; to provide a device which is variable at will for causing an intermittent or periodic operation of an essential mechanism of a dyeing machine; to provide 25 means for automatically stopping certain moving parts of a dyeing machine when such part or parts reach a predetermined position in the cycle of operations; to provide means for causing a rotatable part of a dyeing machine to always 30 come to rest in the same relative position; to provide means for causing long or short rest periods between operating movements of a material lifting mechanism forming part of a material 35 treating machine; and to provide other improvements as will hereinafter appear.

In the accompanying drawings Fig. 1 represents a side elevation of a dyeing machine embodying one form of the present invention; Fig. 2 represents on an enlarged scale a section on line 2—2 of Fig. 1; Fig. 3 represents a detail in part section of the lift rod operating mechanism and brake control; Fig. 4 represents a front elevation of the limit switch and associated parts, the housing cover being removed; Fig. 5 represents a section on line 5—5 of Fig. 4; Fig. 6 represents a diagram of the control circuit; Fig. 7 represents a detail of a portion of the perforated material support and showing in section one of the end flanges; and Fig. 8 represents a detail in 50 elevation of a part of the front of the machine.

Referring to the drawings, one form of the present invention consists of a tank 10 for holding a supply of liquid 11, such as dye, finishing solution, or any other treating liquid, and is preferably of open top construction to allow the ma-

terial to enter the tank and hang suspended above the treating liquid. In the present instance and by way of example, the material shown is in the form of hanks of yarn 12 and may be of coarse material, such as wool or cotton, or of the finer grades of material, such as silk and rayons, all of which can be efficiently treated by means of the present invention.

For suspending the hanks 12 within the tank and with the lower ends thereof above the treating liquid 11, a tubular support 13 is mounted to extend transversely across the open top of the tank 10 and is fixedly mounted at one end in a clamping bracket 14 which is secured to and supported by the main frame 15 for mounting the tank 10. The bracket 14 as here shown has a cap plate 16 bolted thereto for anchoring the support 13 against relative movement. Thus the support 13 is held fast at the end which projects beyond the side of the tank 10 while the major portion thereof extends horizontally above the open top of the tank 10 in such a position that when the hanks 12 are placed thereon the lower ends will allow the excess treating liquid to return to the main supply. The hanks 12 can be freely placed on or removed from the support 13 since its outer end is unobstructed and therefore can be inserted through the loops of material to permit the latter to be properly placed. In connection with the free end of the support 13 it will be noted that it is closed by a cap 17 20 removably attached to a sleeve 18 fixed to the support 13 and having a flange 19 serving as a guide to prevent the hanks from improperly working off of the end of the support. By closing 25 the end of the support with a removable cap 17 it makes possible the cleansing of the inside of the support whenever necessary. Thus by taking off the cap 17 and starting the pump a complete flushing of the tubular support takes place 30 and all sediment, dirt or deleterious particles can be washed out. This ensures the discharge perforations 20 against clogging and against particles lodging therein to project and damage the 35 yarn. A like sleeve and flange are located at the opposite end of the support 13 and for convenience are identified by the same reference numerals. The major portion of this flange 19 is sector shaped in cross section to present a relatively wide curved guide disposed toward the 40 supported material. Thus with the two convex guides facing each other there is no chance for the material to escape axially from the support 13.

In order to deliver the treating liquid to that 55.

portion of the hanks which rests upon the support 13 so that the individual skeins of material are separated and uniformly saturated while the excess liquid can run down the skeins, the upper 5 surface of the fixed support 13 is provided with one or more rows of perforations 20, and in the preferred form of the invention there are six such rows, three are at each side of the top medial support line of the support 13. The rows of 10 each set of three are preferably staggered with respect to each other in order to give the desired distribution of the discharging liquid. The fixed end of the support 13 is connected to and communicates with a pipe 21, here shown as vertically disposed and terminating at its lower end in a connection 22 with the discharge end of a pump 23. A valve 24 may be mounted upon the end of the pipe 21 for drain purposes as will be understood. The pump 23 is driven from any suitable 15 source of power and has an intake pipe 25 connected to the tank 10 at its bottom and communicating with the interior thereof, whereby the liquid can be withdrawn from the tank and circulated by way of the tubular connections to the support 13 and from whence it is discharged 20 by way of the perforations 20.

For lifting the skeins of yarn or other material from the support 13 at predetermined intervals in order to change the position of the hanging material with respect to the support a lifting rod 26 is provided and supported at its ends respectively in two hanger arms 27 which extend radially from the support a sufficient distance to give the desired lift to the material when the rod 30 is revolved about the support 13 as an axis. The arm 27 at the free end of the support 13 is journaled upon the end of the support 13 in any suitable manner. The other arm 27 is connected to a tubular hub 30 which is keyed as shown at 35 31, or otherwise made fast to a sleeve 32 which is supported for rotation upon a bearing carried as a part of the bracket 14. This sleeve 32, as here shown, has a spiral gear 33 formed thereon and in mesh with a worm gear 34 upon the driven counter-shaft 35. These intermeshing gears which form the means for transmitting motion to the arms 27 are suitably housed within case plates 36 and a case cap 37 as will be understood. Preferably also thrust collars 38 are arranged at 40 opposite sides respectively of the gear 33 as will be evident. In connection with the arms 27 it should be noted that the hub 28 of each is axially extended so that the inner face thereof is brought substantially into the vertical plane 45 which includes the flanges 19 at the opposite ends respectively of the support 13. This extended portion of the hubs 28 is of curved contour so that during the lifting movement of the arm the convex face thereof will serve as a stop and guide to prevent the yarn or other material from moving endwise on the rod and also insuring that it be directed or guided onto the adjacent wide curved face forming the upper portion of the respective flanges of the support 13. The counter-shaft 35 is driven through suitable gearing 41 from a motor shaft 42 of the motor 43 which is suitably mounted upon a part of the main frame of the machine. Preferably the motor 43 is of the two phase type and its operation 50 is under the control of a magnetic switch 44 as will be explained.

For the purpose of controlling the operation of the motor 43 so that the material lifting rod 26 will rotate in a predetermined manner a magnetic control coil 45 for the switch 44 is

included in an electric circuit having a conductor 46 leading from one side of the coil 45 to the positive pole of a single phase source of current, while the opposite side of the coil 45 is connected by a conductor 47 which connects the stationary contacts 48 and 49 of the switches 50 and 51 in parallel relation. A branch conductor 52 leads from the conductor 47 to a contact 53 which forms one terminal of a circuit selecting switch of which 54 is another stationary contact and 55 is the movable contactor arranged to move into contact with one of the other contacts 53 or 54 according to requirements. The contact 54 is connected by a conductor 56 to the contactor 57 of the switch 51 10 and this latter is arranged to engage the contact 49 to close this branch of the circuit. Normally the contactor 57 is held flexed against its spring tendency to close the contacts by an extension wiper 58 preferably formed integral therewith and arranged to travel upon the periphery of a timing cam 59 and which is provided with a gap 60 of such a depth as to insure the wiper 58 moving radially inward when it leaves the periphery of the cam 59 to close 15 the circuit between the contactor 57 and the contact 49. The circumferential length of this gap 60 is sufficient to insure a closing of the circuit long enough so that the rod 26 starts upon its rotation about the support 13. The cam 59 20 is preferably driven by a constant speed induction motor of any well known type and need not here be shown nor specifically described since all that is required for an understanding of the present invention is that this cam 59 25 is driven at a constant speed. The contact 54 is also connected by a conductor 61 to the movable contactor 62 of the switch 50 and this is arranged through its spring action to close the circuit at this point whenever the wiper element 64 of the contactor 62 is picked up by the periphery of a rotatable limit cam 65 having a gap 66 of sufficient depth to allow the contactor 62 to move away from the contact 48 and break the circuit when in this position. When 30 the wiper element 64 rides upon the periphery of the limit cam 65 the circuit of the coil 45 is closed. The limit cam 65 is mounted with its gap 66 in a definite relation to the gap 60 in the cam 59 and in the arrangement shown the two control elements 59 and 65 are shown in 35 Fig. 6 with both switches open and the wiper 58 just ready to drop into the gap 60 of the cam 59 to close the circuit through the coil 45, while the wiper element 64 is in the gap 66 and the two contacts 48 and 62 are spaced apart. The mounting for the limit cam 65 consists of a shaft 67 suitably journaled in a supplemental housing 68 and on this shaft 67 is a gear 70 meshing with a gear 71 upon the counter shaft 60 35. The gear ratio is such as to cause the limit cam 65 to rotate in synchronism with the arms 27 and the initial setting of the limit cam is such that the gap 66 is at its lowest position when the rod 26 is at rest in the lowest position. 45

For the purpose of stopping the motor 43 at the instant the motor circuit is broken a magnetic brake 72 is mounted so that its shoes 73 and 74 operatively straddle a brake wheel 75 fast upon the motor shaft 42 and are arranged 50 to be held in non-braking position through lever system 76 and a solenoid 77 which is included in a branch circuit shunted from the motor circuit proper. A coil spring 78 is operatively associated with the lever system and serves to 55

throw the shoes 73 and 74 to braking relation upon the wheel 75 when the solenoid 77 is de-energized by the opening of the motor circuit. Thus by the provision of the limit cam 65 the 5 rotation of the arms 27 brings the gap 66 to the circuit breaking point simultaneously with the arrival of the lift rod 26 at that point and hence the circuit through the motor 43 and the solenoid 77 is broken and the brake shoe 73 and 74 10 act to stop and hold the lift rod 26 in the predetermined rest position.

For the purpose of making and breaking the circuit by which the rod 26 is caused to rotate, the movable contactor 55 is connected by a conductor 80 to one side of a limit switch 81 which has its opposite side connected by conductor 82 to the negative pole of the source of current. This source of current has its opposite or positive pole connected by a conductor 46 to a coil 20 45. The function of the limit switch 81 is to control the current supply to the motor which operates the lift rod 26 and since it is desirable, more particularly for safety's sake, that the lift rod 26 be not operated when there is no 25 liquid being supplied to the discharge tube support 13, this switch 81, in the present instance, is so located and arranged as to be under the control of the mechanism which arranges the path of circulation of the treating liquid from 30 the pump 23. Thus as seen in Fig. 1 and Fig. 8 the switch 81 is of the plunger type having its movable plunger 83 spring pressed outwardly to switch breaking position by a well known spring mechanism and into the path of a plunger operating rock-arm 84 which is fast at its lower end upon a pin 85 supported by a hanger bracket 86. For throwing the rock-arm 84 in a direction to press the circuit closing plunger 83 inwardly of the switch 81, a vertically operated 35 shift member 87 is mounted for vertical reciprocation in bracket lugs 88 and at its upper end carries a part 90 which projects laterally to pick up the rock-arm 84 and also the end of the shift member 87 has a slotted pivotal connection 91 with the short arm 92 of a bell crank 93 which is fixed to the rotatable actuating rod 94 by which the three-way control valve 95 is actuated. The long arm of this bell-crank 93 terminates in a handle 96 disposed at 40 a convenient place for ready operation. It will thus be apparent that when the bell-crank arm 93 is rocked in one direction it will rotate the control rod 94 to cut off the supply of treating liquid to the support 13 and by-pass it back 45 to the tank 10 and at that time it will be in the position shown in Fig. 1 with its part 90 out of engaging position with the rock-arm 84 so that the switch controlling plunger 83 is in open circuit position. As soon as the lever arm 93 is rocked in the opposite direction the rod 94 returns the circulating control valve to its 50 position to admit treating liquid to the support 13 simultaneously the shift member 87 engages the rock-arm 84 and closes the switch so that the motor circuit is closed to cause the lift rod 26 to rotate when called for by the control apparatus.

By reference to Fig. 7 it will be noted that a single discharge opening 109 is provided in the 55 support 13 and occupies a position substantially mid-way between the two uppermost rows of perforations but is located transversely considered in the plane of the first transverse row of perforations. In other words it lies in the row 60 of perforations next adjacent the flange 19.

There are two of these holes 109, one at each end of the support and their function is to discharge an additional stream of liquid at each end of the imperforate material supporting area, and these discharging streams prevent what would otherwise be two localized untreated areas. Thus the full supply of liquor is uniformly distributed against the end flanges and spreads over the material in the most effective manner.

In describing the rotation of the mechanism 10 of the present invention reference will be had more particularly to Fig. 6 of the drawings and it will be assumed that the cam 59 has been started and is rotating at the constant predetermined speed. With the cam 59 in operation the machine can be started to control the lift rod 26 by closing the control switch 81. In the present instance the control switch 81 is closed at the time the hand lever 96 is thrown to admit treating liquor to the treating tube and is caused by the vertical movement of the shift member 87 and consequent rocking of the arm 84 into engagement with the switch closing plunger 83.

Assuming that it is desired to rotate the lift rod 26 intermittently, that is to say to cause it to make one revolution, then rest for a given period, and then make another revolution, the contactor 55 is thrown to the right as seen in Fig. 6 and into contact with the contact 54 and the circuit thus closed is the one which will bring about intermittent operation of the lift arm by the following circuit. The rotation of the cam 59 in counter-clockwise direction causes the wiper 58 to drop into the gap 60 and thereby bring the contactor 57 into electrical contact with the contact 49 to close the circuit by way of conductor 56, contact 54, contactor 55, conductor 80, switch 81, conductor 82 to the source of current and thence by way of conductor 46 to the magnetic coil 45 and conductor 47 back to the contact 49 and contactor 57. This closed circuit energizes the coil 45 so that the magnetic switch 44 is moved to close the circuit which starts the motor 43. The rotary motion of the 45 motor shaft 42 is transmitted through the gears 41 to the counter shaft 45 which in turn drives the worm 34 and gear 33, and gear 71 and 70 so that on the one hand the sleeve 32 causes rotation of the lift rod 26 and on the other hand the rotation of the limit cam 65. The cam 65 and rod 26 travel in synchronism and the gap 66 is always aligned with the rod 26. In view of the relative positioning of the parts 59 and 65, in so far as the initial setting of the 55 gaps 60 and 66 are concerned, the wiper 64 leaves its gap 66 almost immediately after the wiper 58 has entered the gap 60, and hence when the latter wiper 58 rides out of the gap 60 and breaks the contact between the points 49 and 57, the circuit through the magnetic coil 45 remains closed because the contactor 62 is now against the contact 48. The circuit now follows conductor 61, contact 54, contactor 55, conductor 80, switch 81 to the source of current 65 and from the other pole of the source of current by way of conductor 46, coil 45, conductor 47 to contact 48, and contactor 62. It will thus be evident that the coil 45 which serves to make and break the motor control switch 44 is now 70 directly under the control of the circuit including the switch 50, and hence when one revolution of the segment 65 is completed and the rod 26 has reached its normal position then the gap 66 will again be at the point where the wiper 64 75

can drop into it to break the circuit between the contact 48 and the contactor 62. The breaking of this circuit at once deenergizes the coil 45 to thereby break the motor circuit and stop the 5 motor. Since the magnetic brake 72 is also controlled by the circuit which energizes the motor 43 the coil of the solenoid 77 will be deenergized and thereby release the control levers so that the brake shoes instantly grab and hold the 10 wheel 75 which is fast upon the shaft 42 to stop the rod 26 in its predetermined position.

When it is desired to rotate the lift rod 26 continuously the contactor 55 is moved from the contact 54 to contact 53 and thereby closes a 15 different circuit through the electro-magnet 45 and the latter becomes continuously energized. The circuit so closed is from the contactor 55 to contact 53, conductor 52, conductor 47, coil 45, conductor 46 through the source of current to conductor 82, switch 81, conductor 80 back to the contactor 55. In this way the machine is capable of selective operation so that for some 20 kinds of goods the rod 26 will rotate continuously and in other classes of goods it will rotate only at predetermined intervals. All rotation of the lift 25 rod 26 can be dispensed with if desired by placing the contactor 55 in a neutral position where it is out of contact with both contacts 53 and 54.

Throughout the foregoing description reference 30 has been made to the treatment of skeins of yarn, but it is to be understood that this is only by way of example and that the machine is adapted for the treatment of piece goods or material in any other form and wherever the 35 term "skein" appears it is not used in any sense as limiting the scope of the invention.

While only a single form is shown in which this invention may be embodied, it is to be understood that the invention is not limited to 40 any specific construction, but might be applied to various forms without departing from the spirit of the invention or the scope of the appended claims.

Having thus described our invention, we 45 claim:

1. In a dyeing machine the combination of a support for suspending material, a device mounted to rotate about said support for lifting said material from said support, a circuit including a motor for rotating said device, a timing mechanism for closing said circuit at predetermined intervals, means for opening said circuit when said device reaches a predetermined point, and means responsive to the breaking of said 55 circuit for stopping said device at said point.

2. In a dyeing machine the combination of a support for suspending material, a device mounted to rotate about said support for lifting said material from said support, a motor for rotating said device, a circuit including a switch for controlling said motor, electro-magnetic means for controlling said switch, a control circuit including said magnetic means, a timing mechanism for intermittently closing said control circuit, means for opening said control circuit at a predetermined point in the travel of said lifting device, a brake for said motor, and means controlled from said motor circuit for actuating said brake to stop said device at a predetermined point.

3. In a dyeing machine the combination of a support for suspending material, a pair of arms mounted to rotate about said support as an axis, a rod connecting the free ends of said arms and in rest position being below said support and in

the vertical plane passing through said support, means including an electric motor for rotating said arms about said support to change the position of the material on said support, a circuit including a switch and a source of current for operating said motor, and means effective in the rest position of said rod for causing said switch to open said motor circuit.

4. In a dyeing machine the combination of a support for suspending material, a pair of arms mounted to rotate about said support as an axis, a rod connecting the free ends of said arms and in rest position being below said support and in the vertical plane passing through said support, means including an electric motor for rotating 10 said arms about said support to change the position of the material on said support, a circuit including a switch and a source of current for operating said motor, time controlled means for closing said motor circuit, and means effective 15 in the rest position of said rod for causing said switch to open said motor circuit.

5. In a dyeing machine the combination of a support for suspending material, a device mounted to rotate about said support for lifting 20 said material from said support, a motor for operating said device, a circuit for energizing said motor to cause continuous operation of said device, a second circuit for energizing said motor, automatic means for breaking said second circuit to cause periodic operation of said motor, and a switch means for selectively controlling said circuits.

6. In a dyeing machine the combination of a support for suspending material, a device 30 mounted to rotate about said support for lifting said material from said support, a motor for operating said device, a circuit for energizing said motor to cause continuous operation of said device, a second circuit for energizing said 40 motor, automatic means for breaking said second circuit to cause periodic operation of said motor, a switch means for selectively controlling said circuits, and a brake mechanism rendered operative by the opening of said second circuit 45 for stopping the rotation of said device.

7. In a dyeing machine the combination of a support for suspending material, a device mounted to rotate about said support for lifting said material from said support, means including a motor for operating said device, a circuit for energizing said motor, a control circuit including means for opening and closing said motor circuit, two switches connected in said control circuit in parallel relation, a timing device for periodically opening and closing one of said switches, and an element arranged to rotate synchronously with said lifting device for actuating said second switch so that said control circuit is maintained closed after said timing device switch has opened and remains closed until said rotating element breaks said control circuit.

8. In a dyeing machine the combination of a support for suspending material, a device 65 mounted to rotate about said support for lifting said material from said support, means including a motor for operating said device, a circuit for energizing said motor, a control circuit including means for opening and closing said motor circuit, two switches connected in said control circuit in parallel relation, a timing device for periodically opening and closing one of said switches, an element arranged to rotate synchronously with said lifting device for actu- 70

ating said second switch so that said control circuit is maintained closed after said timing device switch has opened and remains closed until said rotating element breaks said control circuit, and means associated with said rotating element for breaking said control circuit when said lifting device is in a predetermined position.

9. In a dyeing machine the combination of a support for suspending material, a device mounted to rotate about said support for lifting said material from said support, means including a motor for operating said device, a circuit for energizing said motor, a control circuit including means for opening and closing said motor circuit, two switches connected in said control circuit in parallel relation, a timing device for periodically opening and closing one of said switches, an element arranged to rotate synchronously with said lifting device for actuating said second switch so that said control circuit is maintained closed after said timing de-

vice switch has opened and remains closed until said rotating element breaks said control circuit, means associated with said rotating element for breaking said control circuit when said lifting device is in a predetermined position, and an electro-magnetic brake for stopping said device in said predetermined position.

5

10. In a dyeing machine the combination of a support for suspending material, a device mounted to rotate about said support for lifting said material from said support, means including a motor for operating said device, a control circuit including means for opening and closing said motor circuit, an element arranged to rotate synchronously with said lifting device for opening said control circuit, a brake means for stopping said lifting device when said motor circuit opens, and a timing mechanism for periodically closing said control circuit to release said brake and start said motor.
